UNITED STATES PATENT OFFICE.

OTELIA A. HOEGLUND, OF CINCINNATI, OHIO.

UNION OR ONE-PIECE UNDERGARMENT.

Application filed December 17, 1923. Serial No. 681,135.

My invention relates to union or one-piece undergarments for ladies and misses. The objects of my invention are to provide a one-piece undergarment adapted to take the place of the usual drawers and brassière; to provide an undergarment adapted to snugly fit the body lines of an individual whereby a neater and more accurate fit of the outer garments may be obtained, thereby insuring the wearer greater comfort and preventing creeping or bunching of the undergarment when the wearer is engaged in vigorous exercises, such as basket ball or other athletic sports; to provide a garment adapted to effect economy and convenience to the wearer as by providing a single garment adapted to efficiently and satisfactorily dispense with the usual straight line athletic garment whereby considerable material is saved in constructing my garment to snugly fit the body lines of the wearer and consequently affording a garment adapted to insure an individual greater comfort; and to provide efficient and convenient means for opening and closing the seat portion of my garment.

Other herein set forth advantages are obtained as my invention consists in providing an upper portion or waist consisting of a plurality of sections of textile material shaped and stitched together in such a manner as to adapt the garment to snugly fit the body lines of an individual and releasable means for fastening said upper portion around the wearer; in providing a band of textile material cut on a bias and stitched to the upper edge of said upper portion; in providing shoulder straps fixed to the upper edge of said upper portion and so arranged that when the garment is in a normal position on the wearer, the straps slant outwardly thereby tending to maintain the straps in proper supporting position; and in providing a lower portion or drawers having its upper edge stitched to the lower edge of said upper portion and having releasable fastening means adjacent the waist of the wearer whereby the usual rear opening in the garment may be quickly and efficiently opened or closed.

My invention also consists in the combination and arrangement of parts as herein set forth and claimed.

In the drawings:

Fig. 1 is a perspective front view of my garment upon a person;

Fig. 2 is a perspective rear view of my garment upon a person;

Fig. 3 is a perspective front view of my garment shown in modified form upon a person;

Fig. 4 is a rear elevation showing my garment in an open position; and

Fig. 5 is a section taken on a line corresponding to 5—5 of Fig. 2.

The undergarment 1 as preferably constructed in accordance with my invention is provided with shoulder straps 2 secured by stitching 3 and 4 to the upper edge and sufficiently near the center 5 thereof so that the straps when in normal position extend slightly outwardly as clearly shown in Fig. 1 and Fig. 2 whereby the straps are prevented from outward movement and from slipping off of the shoulders of the wearer. For convenience in describing the garment the portion as shown above line 5—5 of Fig. 2 will be designated as waist 6 and the portion as shown below line 5—5 of Fig. 2 will be designated as drawers 7. The waist 6 comprises front 8 having its vertical edges 9 stitched to front vertical edges 10 of side pieces 11 and back pieces 12 and 13 having their outer vertical edges 14 stitched to the rear vertical edges 15, respectively, of side pieces 11. The front vertical edges 10 of side pieces 11 are cut slightly angular to rear vertical edges 15 for the purpose of insuring the garment to snugly fit the body lines of a person. Back piece 13 is provided with spaced apart hooks 16 vertically aligned and fixed adjacent rear vertical edge 17 from the top to the bottom of waist 6, and back piece 12 is provided with spaced apart eyes 18 arranged in similar manner as hooks 16 and extending from the top to the bottom of the back piece adjacent its inner vertical edge and fixed to a double thickness of material to prevent the cooperating hooks from causing the wearer discomfort by gouging into the flesh or irritating when in engagement with eyes 18, for fastening the garment around an individual.

The front piece 8 is provided with darts 19 adapted to cause the waist 6 of my garment to snugly fit the body lines of an individual. The material in hem 20 is cut on a bias and stitched to and extends around the top edge of waist 6 for the purpose of adapting the garment to conform to the body curves of the wearer, as well as to render the garment neat and attractive.

The drawers 7 comprises front piece 21, rear pieces 22 and 23, and flaps 22' and 23'. The vertical edges 24 and 25 of front piece 21 are respectively stitched to vertical outer edges 26 and 27 of rear pieces 22 and 23. The vertical inside edges of the rear pieces are stitched to the vertical inside edges of the front pieces from the lower edge 28 of the drawers 7 to crotch 29 whereby legs 7' 10 are formed.

Opening 30 extends from the upper edge 31 of drawers 7 to crotch 29. The flaps 22' and 23' are respectively stitched to rear pieces 22 and 23. Button-holes 32 in flap 23' and rear piece 23 receive buttons 33 fixed to flap 22' and rear piece 22 for securing the garment around the waist of an individual. The line of the crotch 29 is considerably longer thereby providing comfort to the wearer as no binding may be experienced. The buttons 33 are fixed adjacent the waist line 5—5 thereby assuring the flaps 22' and 23' to remain in buttoned position as the movement of the body is less 25 at the waist. The upper edge of drawers 7 is supplied with darts 34 adapted to cause the garment to snugly fit the waist line of an individual. The upper edge of the drawers and the lower edge of the waist are stitched 30 at seam 35 extending from one side piece 11 to the other for the purpose of securely securing the waist and drawers together. The usual hem 36 is formed at the lower edge 28 of drawer legs 7' for the purpose of 35 giving the garment an attractive appearance as well as to prevent the material from which the garment is made from fraying.

As shown in Fig. 3 the lower edges of the legs 7' may be stitched in attractive form as 40 most suitable and desirable for individuals desiring attractiveness; also for the purpose of retaining the warmth of the body within the drawers legs. Front piece 21 of drawers 7 is split to 37 thereby forming an overlapped opening in the front portion of the garment.

As shown in Fig. 2 the lower front edge 38 of the legs 7' when in normal position are elevated above the plane of the rear lower edges 39 of the legs for the purpose of providing a garment adapted to permit the wearer freedom in assuming various positions without the likelihood of the front portion of the garment being pulled downwardly as by contacting the knees of the wearer.

I have, therefore, invented a simple, efficient, economical and practical one-piece undergarment especially desirable for comfortable wear on an individual when engaged in the most strenuous bodily movement, such as athletic sports. In form and construction my garment is especially desirable for the purpose of providing great freedom 60 of motion for the wearer without the likelihood of the usual bunching or binding of underwear such as is customary in two-piece underwear or straight line single piece union suits. My garment is cut and designed to snugly fit the body lines of an individual 70 thereby adapting it to remain in an intended position on the body of the wearer. The lower front edges of legs 7' are, when in normal position, vertically higher than the lower rear edges of the legs and the garment is so constructed that the material in the front portion of the legs normally stands a considerable distance from the legs of the wearer thereby insuring the wearer freedom in stooping without the likelihood of the 80 knees engaging the legs of the garment without the tendency of pulling the garment downwardly and out of its proper position. The overlapping flaps 22' and 23' are buttoned in position as clearly shown in 85 Fig. 5 to adapt the garment to lie smoothly against and in contact with the body of the individual whereby considerable comfort is assured the wearer of my garment, as well as providing a snug fit for the undergarment 90 whereby the outer garments are permitted to conform to the curves of the body thereby securing greater attractiveness and neatness.

The top of the waist is shaped to conform 95 to the contours of the body and is finished with a bias band which keeps it snug without binding. The straps being attached at a slight slant prevents them from slipping down over the shoulders. The three darts 100 in the waist take up the fullness and shape the front of the waist, and being stitched flat do not add bulkiness.

The drawers while fitted to conform to the shape, are roomy and dispense with all unnecessary material. Because the suit fits the body, the most strenuous bodily movements can be made without the suit creeping up or binding as is often the case with loose unfitted suits. The line of the "facing" of 110 the opening or "flap" is long, thereby allowing ease in bending or sitting. The flap doubling over and securely fastening prevents the garment from spreading apart, which is otherwise very uncomfortable and 115 irritating.

The feature of opening the entire garment from top to bottom makes it not only easy to launder but also very easy to put on, adjust and remove.

While I have shown and described a particular construction it will be understood that my invention is capable of some modification without departing from the spirit or scope thereof as defined in the claim.

What I claim as new and desire to secure by Letters Patent is:

A union or one-piece undergarment comprising a waist and drawers, said waist consisting of a front piece, two back pieces and 130

two side pieces, said front piece secured to said side pieces by vertical seams, said back pieces secured to said side pieces by vertical seams, releasable means attached to the inner vertical edges of said back pieces for detachably connecting said garment around the body of the individual, means for supporting said garment on the body of the individual, the lower edge of said waist secured to the upper edge of said drawers consisting of a front section and two back sections, said front section secured to said back

section by vertical seams, said front section split part way from its lower edge thereof and vertical edges formed thereby stitched to the inside vertical edges of said back sections whereby legs are formed in said drawers, tapered flaps fixed to the vertical inside edges of said back sections and releasable means for securing said flaps adjacent the waist line of said garment when said flaps overlap the adjacent back section. 15 20
